UNITED STATES PATENT OFFICE.

HARRY G. BALTHASAR, OF ST. LOUIS, MISSOURI, ASSIGNOR TO COMBINATION AUTO LOCK COMPANY, OF ST. LOUIS, MISSOURI, A CORPORATION OF MISSOURI.

COMBINATION-LOCK FOR MOTOR-VEHICLES.

1,289,080.

Specification of Letters Patent. Patented Dec. 31, 1918.

Application filed November 12, 1917. Serial No. 201,479.

To all whom it may concern:

Be it known that I, HARRY G. BALTHASAR, a citizen of the United States, residing at the city of St. Louis, in the State of Missouri, have invented certain new and useful Improvements in Combination-Locks for Motor-Vehicles, of which the following is a specification.

This invention relates to automobile locks of the type in which a movable valve is interposed between the carbureter and the intake manifold. While the drawings show and the specification describes the said valve in this device as so located, substantially if not identically the same result can be attained by locating the said valve at a suitable point in the exhaust manifold, the construction of the device and its mode of operation being identical whether its location is relative to the exhaust manifold or the intake manifold.

In the accompanying drawings forming a part of this specification, in which like numbers of reference denote like parts wherever they occur,

Figure 1 is a diagrammatic side elevation showing the instrument board of a motor vehicle, the engine, the intake manifold, the carbureter, and this lock and its operating means in proper relation thereto;

Fig. 2 is a sectional view through the instrument board and the device thereon for turning the flexible shaft that operates the combination lock composed of permutation tumblers;

Fig. 3 is an elevational view on the line 3—3 of Fig. 2, looking in the direction of the arrows;

Fig. 4 is a view of Fig. 2, looking in the direction of the arrows of line 4—4 in Fig. 2;

Fig. 5 is a view on the line 5—5 in Fig. 2, looking in the direction of the arrows;

Fig. 6 is a view on the line 6—6 in Fig. 2, looking in the direction of the arrows;

Fig. 7 is a side elevation of this lock in position between the carbureter and intake manifold;

Fig. 8 is a front elevation of the lock disjoined from the carbureter and intake manifold;

Fig. 9 is a detail view of the end of the flexible shaft;

Fig. 10 is an end view of the extreme inner end of the flexible shaft taken at a right angle to Fig. 9;

Fig. 11 is a view on the interior of the lock with the front plate and intake manifold shown in Fig. 7 removed;

Fig. 12 is a sectional view on the line 12—12 in Fig. 11, looking in the direction of the arrows;

Fig. 13 is a sectional view on the line 13—13 in Fig. 11, looking in the direction of the arrows;

Fig. 14 is a fragmental front elevation of the permutation tumblers after the dissolution of the combination; and

Fig. 15 is a section taken on the line 15—15 in Fig. 14, looking in the direction of the arrow.

The chassis 1 supports the radiator 2, instrument board 3, and engine 4 in the usual manner.

The intake manifold 5 extends from the cylinders as is common and the carbureter 6 is bolted thereto by the usual bolts 7 which pass through holes in the flanges 8 and 9 in the carbureter and intake manifold respectively and through the slotted holes 10, 11, and 12 respectively in the body plate 13, intermediate plate 14, and body plate 15. Fig. 8 shows in dotted lines the approximate shape and arrangement of body plate 15 (to which plates 13 and 14 correspond) in case this lock is to be fitted to the V-type engine 85 of an eight or twelve cylinder engine.

When nuts 16 are tightened on bolts 7 passing through the holes 10, 11, and 12, this lock is tightly fastened between the carbureter 6 and the intake manifold 5, and removal of this lock from between the same will leave the carbureter and intake manifold dismounted, disconnected, and in inoperative condition.

Turning the knob 17 in either direction revolves the flexible shaft contained within the housing 18, which shaft will be preferably of three-ply flexible shaft material so as to be acutely responsive to the slightest movement of the knob 17 and also so as accurately to transmit any such slight movement to the rod 19 forming the end of the flexible shaft and by its bifurcated head 20 being attached by pin 21 to arbor 22 on which the permutator tumblers 23, 24, and 25 are mounted. Tumbler 23 is provided with a cam face 26.

The dial 27 is revolved on knob 17 relative to plate 28, the nose 29 being of different shape from the tail 30 and thus indicat-

ing the degree of movement or rotation of the dial 27 relative to the index point 31. The said degree of rotation may be determined also by the ball 32 riding into and 5 out of the notches 33, the said ball being spring pressed by spring 34. On account of the flexibility of the shaft within housing 18 and of the said housing, connection is easily made between the rotatable knob 17 10 and the arbor 22, no matter where the carbureter 6 may be located relative to the instrument board 3.

Pin 21 is adapted to slide in slot 35 in head 20 in tight connection with the flexible 15 shaft by means of the rod 19. While pin 21 can slide in slot 35 in a longitudinal direction the turning of head 20 forces turning of the arbor 22 because of the diameter of pin 21 being substantially the same as the 20 width of slot 35. The head 20 of the flexible shaft is in tight engagement with the plate 36 cast integral with body plate 15 of which housing 37 and boss 38 form a part. The head 20 is larger in diameter than the opening 25 through the end 39 of housing 18 and its movement is therefore limited in that direction. The end 39 is gripped and clamped by bolt 40 in jaw 41. This mode of attachment 30 of the flexible shaft to the arbor 22 prevents pulling apart of the permutation tumblers 23, 24, and 25, due to the road stress on the engine or frame of the vehicle and insures prompt and accurate working of the lock because the pin 21 and arbor 22 will 35 be turned by the bifurcated head 20 of the flexible shaft no matter in what part of the slot 35 the pin 21 happens to be.

The arbor 42 is fixed to plate 13 and passes loosely through plate 14 and loosely 40 into a drill 43 in arbor 22.

Tumblers 24 and 25 are so mounted on arbor 42 as to be adapted to rotate around it. Cam tumbler 23 is fixed to arbor 22 but by means of drill 43 is loosely mounted on arbor 42 so as to be adapted to rotate there-around. Pin 44 on tumbler 23 is adapted 45 to engage with pin 45 on tumbler 24. Pin 46 on tumbler 24 is adapted to engage with pin 47 on tumbler 25. The working of the tumblers 23, 24, and 25 by means of knob 17 through the instrumentality of the flexible shaft that terminates in the head 20 brings the slots 48 into alinement opposite arm 49, which is the position shown in Figs. 50 11 and 12. This is the open position, which in rotation in either direction (the direction depending upon the combination) of the knob 17 will cause valve 50 to be moved upward in Figs. 11 and 12 so as to remove it 55 from closing hole 51 in plate 15 and hole 52 in plate 13, the position to which the same is moved being shown in dotted lines in the upper part of Fig. 11. When valve 50 has been moved from the full-line position in 60 Fig. 11 to the dotted line position in the

same figure, gas can pass freely from the carbureter 6 into the intake manifold 5, permitting the operation of the engine, which is impossible when holes 51 and 52 in plates 15 and 13 of this lock are closed by valve 50. 70

Valve 50 slides in an elongated slot 53 in plate 14, one end of the said slot substantially coinciding with the holes 51 and 52 in plates 15 and 13 and the other end of the said slot terminating in the centering cut-out 54 in which the lug 55 seats whenever the valve 50 is fully open. The rounded shape of the corners 56 of the said slot 53 additionally tends to center the said valve 50, which centering as well as the scallops 57 80 in the side of valve 50, tend to prevent binding of the same against the walls of slot 53 during the travel of the valve 50.

Pivoted at 58 in the slot 59 is an arm 60 which at its opposite end is pivoted on arbor 42. 85

Pivoted on stud 61 which is fixed to arm 60 is a trigger 62, to which trigger 62 arm 49 is fixed or of which said arm 49 may form an integral part. A spring 63 is in engagement with the said arm 49 and also with a point of fixation 64 on arm 60, which spring so acts as to tend always to force arm 49 into slots 48 when the three slots 48 are opposite it, i. e., in registration with each other. 90 When one or more of the said slots 48 is not in registration, the periphery of its tumbler holds arm 49 back under pressure of spring 63, which is made possible by the indentation 65 in cam slot 66 in which slot pin 67 travels whenever valve 50 slides in slot 53. The said pin 67 enters indentation 65 only when the valve 50 is in closed position, i. e., covering the holes 51 and 52, and furthermore only when pressure of the periphery of one of the 100 tumblers forces the said pin 67 into the said indentation 65. Pin 67 is released through indentation 65 by such manipulation of the tumblers 23, 24, and 25 as works the combination and causes alinement of the three 110 slots 48. Thereupon the lock stands unlocked and rotation of arbor 22 by knob 17 causes the valve 50 to slide to the open position. Slot 66 and indentation 65 are cut through plate 14 and underlying the same is 115 channel 68. A countersink 69 is preferably cut in the interior side of plate 13 so as to prevent cramping of valve 50 in its movement.

The holes 10, 11, and 12 are elongated to 120 accommodate any variation in size of carbureters and intake manifolds, the valve 50 being made of a size large enough to cover fully the outlet from the carbureter and the intake of the intake manifold in such machines as have those openings of the largest diameter.

Washers 70 are interposed between tumblers 23, 24, and 25 and between washer 25 and arm 60. Spring 71 impinges against 125

the shoulder 72 and forces the tumblers into such proximity to each other as to insure their pins 44, 45, 46, and 47 always making suitable engagement.

- 5 Plates 13, 14, and 15 are fastened together by screws 73, which makes this device when the parts have been assembled between plates 13 and 15 and the said plates together with plates 14 screwed together by screws 10 73, a lock that can be boxed and shipped to any distance and readily attached anywhere to any car.

The dial 74 may be used for various useful purposes, included among which may be mentioned its use as a "phony" until the true combination is determined by readjustment of the tumblers with relation to knob 17 and its associated parts.

It will be understood that if desired tumblers 23, 24, and 25 may be provided with a plurality of holes to permit of change of location of the tumbler pins, such plurality of holes not being shown in the drawings but only one hole indicated for each pin 25 shown.

Countersink 75 in plate 15 is opposite countersink 69 in plate 13.

When the device has been assembled as hereinbefore described, and screws 73 have 30 been inserted in place, the edges of plates 13, 14, and 15 are soldered together, making a unitary whole of the casing composed of the said plates and preventing any air or 35 gas leaks past the edges of the said plates or between the said plates.

The tumblers are first set according to dial 74, then the flexible shaft is led to a point adjacent to instrument-board 3, then shaft 76 is passed through the said board 40 and its end into the split collar 77 having therein a plurality of slots 78 and external screw-threads 79. The dial 27 is then set to the same number as the dial 74, while the flexible shaft is held tight and the nut 80 45 screwed home on threads 79.

Having thus described this invention, I hereby reserve the benefit of all changes in form, arrangement, order, or use of parts, as it is evident that many minor changes 50 may be made therein without departing from the spirit of this invention or the scope of the following claims.

I claim:

1. In a combination lock for motor vehicles, the combination, with a member having an aperture therethrough, of a valve for controlling passage through said aperture, a valve-actuating arm pivotally connected to said valve, rotatable permutation tumblers, and means coöperating with said arm and said tumblers to move said arm to open, close and lock the valve.
- 60 2. In a combination lock for motor vehicles, the combination, with a member having an aperture therethrough, of a valve for controlling passage through said aperture, a valve-actuating arm pivotally connected to said valve, rotatable permutation tumblers, and means coöperating with said arm and said tumblers to move said arm to open, close and lock the valve.

- 65 3. In a combination lock for motor vehicles, the combination, with a member having an aperture therethrough, of a valve for controlling

controlling passage through said aperture, a valve-actuating arm pivotally connected to said valve and movable in the arc of a circle, rotatable permutation tumblers, and means coöperating with said arm and said tumblers to move said arm to open, close and lock the valve.

3. In a combination lock for motor vehicles, the combination, with a member having an aperture therethrough, of a valve for controlling passage through said aperture, a valve-actuating arm pivotally connected, at one end, to said valve and, at the other end, to an axle carrying a plurality of tumblers, and means coöperating with said arm and tumblers to move said arm to open, close and lock the valve.

4. In a combination lock for motor vehicles, the combination, with a member having an aperture therethrough, of a valve for controlling passage through said aperture, a valve-actuating arm pivotally connected to said valve, rotatable permutation tumblers, means coöperating with said arm and tumblers to move the arm to open, close and lock the valve, and means for guiding said valve along a rectilinear path of movement.

5. In a combination lock for motor vehicles the combination, with a member having an aperture therethrough, of a valve for controlling passage through said aperture, a valve-actuating arm pivotally connected to said valve, rotatable permutation tumblers, and means carried by said arm and coöperating with said tumblers to move the arm to open, close and lock the valve.

6. In a combination lock for motor vehicles, the combination, with a member having an aperture, of a valve for controlling passage through said aperture, a valve actuating arm pivotally connected to said valve, rotatable permutation tumblers, and a spring-pressed member carried by said arm and coöperating with said tumblers to permit the arm to open, close and lock the valve.

7. In a combination lock for motor vehicles, the combination, with a member having an aperture, of a valve for controlling passage through said aperture, a valve-actuating arm pivotally connected to said valve, rotatable permutation tumblers, a spring-pressed member carried by said arm and coöperating with said tumblers to permit the arm to open, close and lock the valve, and means for guiding said spring-pressed member when moving in unison with the tumblers to open and close the valve.

8. In a combination lock for motor vehicles, the combination, with a member having an aperture, of a valve for controlling passage through said aperture, a valve-actuating arm pivotally connected to said valve, rotatable permutation tumblers, a spring-pressed member carried by said arm and coöperating with said tumblers to permit the

arm to open, close and lock the valve, and guiding means for said spring-pressed member, comprising a pin carried thereby and movable in an arcuate slot in said apertured member.

9. In a combination lock for motor vehicles, the combination, with a member having an aperture, of a valve for controlling passage through said aperture, a valve-actuating arm 10 pivotally connected to said valve, rotatable permutation tumblers, a spring-pressed member carried by said arm and cooperating with said tumblers to permit the arm to open, close and lock the valve, and guiding means 15 for said spring-pressed member, comprising a pin carried thereby and movable in an arcuate slot in said apertured member, said slot having an angled extension toward one end thereof for receiving said pin when the 20 spring-pressed member is not engaged by said tumblers as aforesaid.

10. In a device of the character described, the combination of a casing having a flexible jaw member, a bolt for tightening the said 25 jaw, a shaft adapted to be held by the said jaw when clamped together, the said shaft having a bifurcated head, an arbor, a pin adapted to connect the said arbor with the said shaft and adapted to slide within the 30 said bifurcation, tumblers actuated by the said arbor, and a slide valve actuated by the said tumblers.

11. In a device of the character described, the combination of a base plate, an arbor 35 fixed thereto, tumblers adapted to rotate around the said arbor, a hollow arbor mounted upon the said first mentioned arbor and bearing a tumbler fixed thereto having a cam, means for actuating the said second 40 mentioned arbor and thereby all the tumblers, and a slide valve adapted to be locked or released by the said tumblers.

12. In a device of the character described, the combination of a base plate and a housing plate, a slide valve adapted to move in 45 either direction in a hollow between the said plates, the said plates having openings therethrough adapted to be closed or opened by the said valve, an arm pivoted to the said 50 valve and adapted to move the same in either direction, a spring-pressed member adapted

to actuate the said arm, and permutation tumblers adapted either to close and lock the said valve or to release and open the same.

13. In a device of the character described, 55 the combination of a base plate and a housing plate, a slide valve adapted to move in either direction in a hollow between the said plates, the said plates having openings therethrough adapted to be closed or opened by 60 the said valve, an arm pivoted to the said valve and adapted to move the same in either direction, a spring-pressed member adapted to actuate the said arm, and permutation tumblers adapted either to close and 65 lock the said valve or to release and open the same, the said arm being slidingly pivoted to the said valve.

14. In a device of the character described, 70 the combination of a base plate and a housing plate, a slide valve adapted to move in either direction in a hollow between the said plates, the said plates having openings therethrough adapted to be closed or opened by 75 the said valve, an arm pivoted to the said valve and adapted to move the same in either direction, a spring-pressed member adapted to actuate the said arm, and permutation tumblers adapted either to close and 80 lock the said valve or to release and open the same, the said spring-pressed member being pivoted to the said arm.

15. In a device of the character described, 85 the combination of a base plate and a housing plate, a slide valve adapted to move in either direction in a hollow between the said plates, the said plates having openings therethrough adapted to be closed or opened by 90 the said valve, an arm pivoted to the said valve and adapted to move the same in either direction, a spring-pressed member adapted to actuate the said arm, and permutation tumblers adapted to lock the said valve or 95 to release and open the same, said tumblers being provided with slots adapted when in alinement to receive the said spring-pressed member, whereupon, by rotating the tumblers in unison in opposite directions, the valve may be opened or closed.

In testimony wherof I hereunto affix my 100 signature.

HARRY G. BALTHASAR.
